UNITED STATES PATENT OFFICE.

HENRIETTA PETTYJOHN BURWELL, OF MAYSVILLE, KENTUCKY.

GARMENT-RECEPTACLE.

1,123,679.

Specification of Letters Patent.

Patented Jan. 5, 1915.

Application filed February 26, 1914. Serial No. 821,222.

To all whom it may concern:

Be it known that I, HENRIETTA PETTYJOHN BURWELL, a citizen of the United States, residing at Maysville, in the county 5 of Mason and State of Kentucky, have invented new and useful Improvements in Garment-Receptacles, of which the following is a specification.

This invention relates to receptacles for carrying garments, and is particularly adapted for holding baby's napkins.

The object of the present invention is to provide a device of this kind, which is easy to carry and is so constructed, that both 15 soiled and dry or clean napkins can be carried without the one contaminating the other.

In the accompanying drawings:—Figure 1 is a perspective view of the invention, 20 with a part broken away for clearness, Fig. 2 is a central section, and Fig. 3 is another perspective view of the device.

In referring to the drawings, like numerals indicate the same parts in the several 25 views.

Numerical 1 indicates a receptacle formed of cloth, having an opening 2 therein, adapted to be closed by the clasps 3. Within this receptacle is an inner pouch 4 of much the 30 same shape, only it is smaller and is adapted to be inserted within the receptacle 1 through the opening 2. The pouch 4 is composed of waterproof material and is provided with an opening 5, which may be 35 closed by clasps 6.

Referring to Fig. 2, it will be noticed that the dry garments or napkins 7 are placed in the receptacle 1, while the soiled ones 8 are held by the inner pouch 4. Thus it will be 40 seen, that the dry and soiled garments or

napkins 7 and 8 are inclosed within the outer receptacle and still are kept from contact with each other by a wall of the inner waterproof pouch 4.

The invention may be made up in an ornamental style by sewing a piece of lace 9 around the periphery of the outer receptacle 1. It thus forms an ornamental pillow or pad upon which a baby may be held, securing the lap of the party holding the baby 45 against disaster in case of accidents. To this end the inner pouch 4 is constructed so that when it is inserted within the receptacle 1 and spread out it will form a complete 50 layer inside of said receptacle, thus serving 55 to make the pad waterproof.

It will be understood from the foregoing, that when a change of apparel is required, the soiled napkin is placed in the pouch 4, while a clean and dry one ready for use, is 60 taken from the outer receptacle 1.

Having thus described my invention, what I claim is:—

A baby pad comprising an outer container 65 having an opening in the side thereof, and adapted to hold dry garments, and an independent waterproof pouch having an opening in the side thereof, and adapted to hold soiled garments, said pouch being adapted to be inserted within said outer container 70 and to cover the entire inner surface thereof to form a waterproof lining for said pad.

In testimony whereof I have hereunto set my hand in the presence of two subscribing witnesses.

HENRIETTA PETTYJOHN BURWELL.
